IGNITION DEVICE

Julius H. Bayard, Seattle, Wash., assignor to
Foster Wheeler Corporation, New York, N. Y.,
a corporation of New York

Application May 10, 1945, Serial No. 592,973

10 Claims. (Cl. 158—10)

1

The present invention relates to ignition devices and more particularly to an ignition device for lighting the firing means of a furnace.

The invention is particularly adapted for use in lighting the burner or burners of furnaces which are wholly or partially surrounded by an air duct, or air chamber, in which the pressure is higher than that existing in the furnace or furnace room. In lighting the burner or burners, it is necessary to pass the ignition device through a port in the air duct or air chamber, across the air duct or chamber, and through another port in the wall of the furnace thence into the furnace chamber. The ignition device is subjected to the air currents from the air duct or chamber, particularly when it is being passed through the duct or chamber, which currents of air normally extinguish an igniter.

The present invention provides an igniter which will not be extinguished by air currents when the igniter is being used to light a burner or burners of a furnace which is wholly or partially surrounded by an air duct or chamber in which the pressure is higher than that existing in the furnace or furnace room.

The invention will be understood from the following description when considered in connection with the accompanying drawing forming a part thereof and in which:

Fig. 1 is a longitudinal sectional view of the igniter of the present invention with the wick thereof uncovered;

Fig. 2 is a view similar to Fig. 1 but with the shield positioned over the wick of the igniter;

Fig. 3 is a transverse sectional view taken on the line 3—3 of Fig. 1;

Fig. 4 is a view similar to Fig. 3 but taken on the line 4—4 of Fig. 1, and

Fig. 5 is a view similar to Fig. 2 illustrating the igniter of the present invention being passed through an air duct toward a furnace chamber.

Like characters of reference refer to the same parts throughout the several views.

Referring to the drawing, the igniter, as shown, comprises a tubular body member 10 having a frusto-conical shaped head 11 at the forward end thereof. The head 11 has an air passage 12 with an inlet 14 in communication with the tubular member and outlet portions 13 which extend substantially parallel to the axis of the tubular member and are adapted to direct air toward the opposite or rearward end of said tubular member, as will hereinafter be fully described. The peripheral surface 15 of the head is horizontally inclined from the end of the head nearest the body member 10 toward the opposite end. A wick 16, which is normally saturated with a combustible fluid, is mounted on the body member adjacent the head 11.

A shield 17 is slidably mounted on the body 60

2

member 10 and is movable axially of said member. The shield 17 comprises a cylindrically-shaped metallic shell 18 which is open at the end thereof facing the head and closed at the opposite end by an end piece 19 on which the shell is mounted. The end piece 19 slidably engages the body member 10 and has a plurality of outlet passages 20 therein which outlet passages extend axially of the shield 17 and body member 10. 10 Actuating handle 21 is secured to the end piece 19 of the shield 17. The end of the body member opposite that on which head 11 is mounted is connected to an air line 22 through which a stream of air flows into the body member. The air line 22 may be connected to any suitable source of air such as, for example, to the air casting 23 shown in Fig. 5. The flow of air through the line 22 is controlled by a valve 30.

In Fig. 5, the present invention is disclosed as being passed through a lighting port 24 in an air casing 23 which is spaced from a furnace wall 25 to form an air chamber 26. The air chamber receives air under pressure from a source such as a blower, not shown. The furnace chamber is designated by the reference numeral 27 and has burner means 29.

In operation, the wick 16 is lighted and the valve 30 in the air line 22 is opened so that a stream of air passes through the line 22 into the tubular body member 10 thence into the air passage 12 in the head 11. From the passage 12, air flows into the outlet portions 13 and is directed toward and over the wick 16. Shield 17 is then moved toward the forward end of the body member 10, on which end the head 11 is mounted, by means of the actuating handle 21 until the shell 18 tightly engages the tapered peripheral surface 15 of the head 11, as shown in Fig. 2. Air from the outlet passages 13 supplies sufficient oxygen to maintain combustion in the wick 16 and to cause flame from the wick to pass toward the end piece 19 and outwardly of the shield 17 through the outlet passages 20. The flame from the outlet passages 20 projects beyond the end piece 19. 40 The ignition device of the present invention is then passed through the lighting port 24 in the air casing 23, as shown in Fig. 5, through the air chamber 26 thence through the lighting port 28 in the furnace wall 25 into the furnace chamber 27. The device is thereafter passed through the furnace chamber into close proximity with a burner or burners 29, which burners are lighted by the flame passing outwardly of the shield 17 through the outlet passages 20. Since the wick 16 is enclosed within the shield 17, the flame from the wick is not extinguished by the air currents in the air chamber 26 or in the furnace chamber 27. The normal flow of the air currents in the air chamber 26 and furnace 27 would be from the forward end of the tubular body member 10, on

which end the head 11 is mounted, toward the rearward end of the shield 17, the end on which the end piece 19 is positioned. The air currents in the chambers 26 and 27, therefore, would normally cause an induced draft which draws the flame through the outlet passages 20. The distance the flame projects beyond the end piece 19 is controlled by means of the valve which controls the flow of air through the line 22 and body member 10. The body member 10 is of a length sufficient to permit reaching of the burners from the outside of the furnace and to permit the use of the rearward part of the body member as a handle without danger of injury to the operator's hands by flame from the passages 20. The shield 17 is of such length as to bring the end piece 19 into close proximity with the wick 16 and to enclose the wick within the shield when the shell 18 is in engagement with the tapered peripheral surface 15 of the head 11. The shell 18 of the shield 17 is normally of sheet metal and is heated to a red heat by the wick 16 within a short time. The heated shell, therefore, assists in lighting the burners.

Since changes may be made in the form, location and relative arrangement of the several parts of the device disclosed without departing from the principles of the invention, it will be understood that the invention is not to be limited excepting by the scope of the appended claims.

What is claimed is:

1. An igniter comprising a tubular body member, combustible means positioned on said body member adjacent one end thereof, a head disposed at said one end of the body member, said head having an air passage with an inlet in communication with the tubular member and an outlet through which air flows toward said combustible means, a shield movable axially of the body member, the shield being open at the end thereof nearest said head and being adapted to pass over the combustible means and be closed at said open end by the head, an end piece closing said shield at the end thereof opposite the open end, said end piece being closely adjacent the combustible means when the shield is in engagement with said head and having an outlet passage in communication with the interior of the shield adapted to direct products of combustion toward the end of the body member opposite said one end, and means through which air is introduced into said tubular body member.

2. An igniter comprising a tubular body member, combustible means positioned on said body member adjacent one end thereof, a head disposed at said one end of the body member and having a peripheral surface horizontally inclined toward said one end, said head having an air passage with an inlet in communication with the tubular member and an outlet through which air flows toward said combustible means, a shield movable axially of the body member, the shield being open at the end thereof nearest said head and adapted to pass over the combustible means and engage the inclined peripheral surface thereof, an end piece closing said shield at the end thereof opposite the open end, said end piece being closely adjacent the combustible means when the shield is in engagement with said head and having an outlet passage in communication with the interior of the shield adapted to direct products of combustion toward the end of the body member opposite said one end, and means through which air is introduced into said tubular body member.

3. An igniter comprising an elongated tubular body member, a wick positioned on said body member adjacent one end thereof, a head mounted at said one end of the body member, said head having an air passage with an inlet in communication with the tubular member and an outlet through which air flows toward said wick, a shield slidably mounted on and movable axially of the body member, the shield being open at the end thereof nearest said head and adapted to pass over the wick and be closed at said open end by the head, an end piece closing said shield at the end thereof opposite the open end, said end piece being closely adjacent the wick when the shield is in engagement with said head and having an outlet passage in communication with the interior of the shield adapted to direct products of combustion toward the end of the body member opposite said one end, and means through which air is introduced into said tubular body member.

4. An igniter comprising an elongated tubular body member, a wick positioned on said body member adjacent one end thereof, a head disposed at said one end of the body member and having a peripheral surface horizontally inclined toward said one end, the head having an air passage with an inlet in communication with the tubular member and outlets through which air flows toward and over said wick, a shield slidably mounted on and movable axially of the body member, the shield being open at the end thereof nearest said head and adapted to pass over the wick and engage the inclined peripheral surface thereof, an end piece closing said shield at the end thereof opposite the open end, said end piece being closely adjacent the wick when the shield is in engagement with the peripheral surface of the end piece and having outlet passages therethrough extending substantially axially of the body member, said outlet passages being in communication with the interior of the shield, and means through which air under pressure is introduced into the tubular body member.

5. An igniter for igniting a burner of a furnace comprising a combustion chamber having an outer wall, an air casing for conducting air under pressure at the side of said wall opposite the combustion chamber side thereof, a burner in said chamber, the casing and the chamber each having a lighting port therein through which the igniter is passed forward end first through said casing and into the chamber in lighting the burner, said igniter comprising an elongated tubular body member having a forward end portion and a rearward portion, combustible means positioned on the body member adjacent the forward end, a head disposed at the forward end, said head having an air passage with an inlet in communication with the tubular member and an outlet through which air flows toward said combustible means, a shield movable axially of the body member, the shield being open at the end thereof nearest said head and adapted to pass over the combustible means and engage the head, an end piece closing said shield at the rearward end, said end piece being closely adjacent the combustible means when the shield is in engagement with said head and having an outlet passage in communication with the interior of the shield adapted to direct products of combustion toward the rearward end of the body member, and means through which air is introduced into the tubular body member.

6. An igniter for igniting a burner of a furnace

comprising a combustion chamber having an outer wall, an air casing for conducting air under pressure at the side of said wall opposite the combustion chamber side thereof, a burner in said chamber, the casing and the chamber each having a lighting port therein through which the igniter is passed forward end first through said casing and into the chamber in lighting the burner, said igniter comprising an elongated body member having a forward end portion and a rearward portion, a wick positioned on the body member adjacent the forward end thereof, a head disposed at said forward end and having a peripheral surface horizontally inclined toward the forward end, the head having an air passage with an inlet in communication with the tubular member and outlets through which air flows toward said wick, a shield slidably mounted on and movable axially of the body member, the shield being open at the end thereof nearest the head and adapted to pass over the wick and engage said inclined peripheral surface, an end piece closing the shield at the rearward end, said end piece being closely adjacent the wick when the shield is in engagement with the peripheral surface of the head and having an outlet passage in communication with the interior of the shield adapted to direct products of combustion toward the rearward end of the body member, and an air conduit in communication with the body member and the air duct, and means for controlling the flow of air from the air duct to the body member.

7. An igniter comprising elongated air conducting means, combustible means positioned adjacent one end of said air conducting means, said air conducting means being operatively associated with an air passage and arranged to direct air toward the combustible means and the opposite end of said conducting means, a head piece adjacent said one end of the air conducting means, a shield movable longitudinally of the conducting means, the shield being open at the end thereof nearest said head and being adapted to pass over the combustible means and be closed at the open end thereof by said head, an end piece closing said shield at the end thereof opposite the open end, said end piece being adjacent the combustible means when the shield is closed by said head piece and having an outlet passage in communication with the interior of the shield adapted to direct products of combustion outwardly and away from the shield, and means through which air is introduced into said air conducting means.

8. An igniter comprising elongated air conducting means, a wick positioned adjacent one end of said air conducting means, said air conducting means being operatively associated with an air passage and arranged to direct air toward the wick and the opposite end of the conducting means, a head piece adjacent said one end of the air conducting means, a shield movable longitudinally of the conducting means, means for imparting longitudinal movement to said shield, the shield being open at the end thereof nearest said head and being adapted to pass over the wick and be closed at the open end thereof by said head, an end piece closing said shield at the end thereof opposite the open end, said end piece being adjacent the combustible means when the shield is closed by said head piece and having an outlet passage in communication with the interior of the shield adapted to direct products of combustion outwardly and away from the shield, and means through which air under pressure is introduced into the air conducting means.

9. An igniter comprising elongated air conducting means, combustible means positioned adjacent one end of said air conducting means, said air conducting means being operatively associated with an air passage and arranged to direct air toward the combustible means and the opposite end of said conducting means, a head piece adjacent said one end of the air conducting means, a shield movable longitudinally of the conducting means, the shield being open at the end thereof nearest said head and being adapted to pass over the combustible means and be closed at the open end thereof by said head, an end piece closing said shield at the end thereof opposite the open end, said end piece being adjacent the combustible means when the shield is closed by said head piece and having an outlet passage in communication with the interior of the shield adapted to direct products of combustion outwardly and away from the shield, means through which air under pressure is introduced into said air conducting means, and means for controlling the flow of air through the air conducting means.

10. An igniter for igniting a burner of a furnace comprising a combustion chamber having an outer wall, an air casing for conducting air under pressure at the side of said wall opposite the combustion chamber side thereof, a burner in said chamber, the casing and the chamber each having a lighting port therein through which the one end of the igniter is first passed through said casing and into the chamber in lighting the burner, said igniter comprising elongated air conducting means, combustible means positioned adjacent one end of said air conducting means, said air conducting means being operatively associated with an air passage and arranged to direct air toward the combustible means and the opposite end of said conducting means, a head piece adjacent said one end of the air conducting means, a shield movable longitudinally of the conducting means, the shield being open at the end thereof nearest said head and being adapted to pass over the combustible means and be closed at the open end thereof by said head, an end piece closing said shield at the end thereof opposite the open end, said end piece being adjacent the combustible means when the shield is closed by said head piece and having an outlet passage in communication with the interior of the shield adapted to direct products of combustion outwardly and away from the shield, and means through which air is introduced into said air conducting means.
